WILLARD HERBERT GILMAN AND DANIEL E. KEMPSTER, OF BOSTON,
MASSACHUSETTS.

TYPE-WRITING MACHINE.

SPECIFICATION forming part of Letters Patent No. 309,780, dated December 23, 1884.

Application filed December 11, 1883. (No model.)

To all whom it may concern:

Be it known that we, WILLARD HERBERT GILMAN and DANIEL E. KEMPSTER, both of Boston, county of Suffolk, and State of Massachusetts, have invented an Improvement in Type-Writing Machines, of which the following description, in connection with the accompanying drawings, is a specification, like letters on the drawings representing like parts.

This invention has for its object to simplify and improve the construction of that class of type-writing machines wherein the type or letters used are carried at the edge of a rotating disk having a vertical movement. In this present invention the rotating type-wheel, set in motion in one direction, as herein shown, by a cord, and in the other direction by a spring, has its shaft supported by pointed bearing-screws held in a metal key made as a yoke-lever pivoted upon a standard erected upon the stationary top of the machine, the hand-piece of the said lever being at one end thereof and the axis of the type-wheel being at right angles to the line being printed, the movement of the paper for spacing between lines being in the direction of the said axes. The paper to be printed upon by the type-wheel, co-operating with an adjustable inking-ribbon, is held upon a longitudinally-movable platen in a carriage having a lateral movement underneath the said stationary top plate, the latter serving to support the spools which carry the inking-ribbon. The lever which operates the type-wheel is provided with a pawl which engages and turns a toothed gear, to be described, that meshes with a rack and moves the paper-holding carriage laterally after each descent of the type-wheel. The index showing the letters and provided with recesses or notches to be engaged by the index-slide held by the operator is placed at one side of the stationary top plate, and the said slide is mounted upon a guide, so that it can be slid thereon and also oscillated as the slide is moved by the hand of and in a direct line toward and from the operator, such direction of movement being easy and natural. The top plate is cut away to permit the paper to be readily seen.

The particular features in which this in-

vention consists will be pointed out in the claims at the end of this specification.

Figure 1 is a plan view of a type-writer embodying our invention, portions of the top plate being broken away to show parts under it. Fig. 2 is a front view of the same. Fig. 3 is a detail showing the rear side of the type-wheel with its operating-spring. Fig. 4 is a detail showing a part of the lever or key to be described, and Fig. 5 is a detail of the alarm or click.

The main or stationary part of the type-writer consists of a top plate, A, placed upon suitable sills, A' A'', thus leaving a suitable space for the reception of the carriage B, having at one end eyes B', which embrace a guide-rod, B'', while the other or rear end of the said carriage has suitable projections to enter a groove, B', in the rear sill, A''. (See Fig. 2.) The guide B'' is extended laterally across the type-writer, and the carriage is moved laterally by means of a toothed wheel, B', which engages a toothed rack, B'', attached to the carriage, leaving, however, a space below the said rack for the reception and longitudinal movement in guideways in the side pieces of the said carriage of the paper-holding platen C, provided at one side with a numbered scale, C', corresponding with the lines to be printed, one or more pointers, C'', on the carriage co-operating therewith, thus enabling the operator to return the platen to position after having inspected the printing. The stationary part of the frame at the right of the carriage B has pivoted upon it at 2 a bell-crank lever, C', having an inclined inner edge, the rear end of the said lever at its inner side being normally held by a spring, 3, in contact with a pin, 4, in which position the said lever, as in Fig. 1, presents the inner edge of its arm next the carriage as a rigid incline, or as a surface which will not move by pressure applied to the inner edge of the lever between its fulcrum and the carriage. The right-hand edge of the platen C is provided with a toothed bar, C', it having a tooth for each line to be printed. As the carriage is moved backward to its extreme right-hand position preparatory to commencing a new line, one of the teeth of the toothed bar C' strikes against the inclined

inner edge of that end of the lever C⁴ nearest the carriage, and the said lever, rigidly held against movement about its pivot by pressure applied to it at its inner edge, as stated, presents a rigid incline, against which the said tooth acts, and, as the lever cannot turn while the tooth slides against it toward the fulcrum of the lever C⁴, results in pushing the platen forward sufficiently to present the paper correctly for a new line to be printed. The platen having been thus moved forward, as described, on the carriage, the latter will be started toward the left with the platen, and at such movement of the carriage and platen 5 a tooth of the toothed bar C³ will act against the outer inclined side of the lever C⁴; but the said lever will not move the platen longitudinally as when the tooth next to it rode over the inner edge of the said lever, for as the 10 said tooth acts upon the outer edge of the said lever the latter turns on its fulcrum away from the pin 4 and against the spring 3, and as the tooth of the toothed bar retires from contact with the said lever, the latter, under the pressure of the spring 3 against one end, is turned 15 on its pivot sufficiently to throw its opposite end toward the operator far enough to permit the tooth which so passes from the outer edge of the said lever to (at the next movement of the carriage and platen to the left) strike 20 against the inner inclined edge of the lever C⁴, thus again causing the forward movement of the carrier independently of the carriage. The platen is held in the position where it is 25 placed by the pawl C⁴ by a catch, e⁵, set in the carriage and acting against the notched left-hand edge of the scale C⁴. The wheel B⁴ has its axle held in a standard, D⁶, secured to the top plate, A, which is cut away as much as 30 possible consistent with strength to leave the platen and paper thereon exposed to view, and the said wheel is moved by a pawl, D, pivoted at D² on an ear of the lever or key E, pivoted at E¹ upon a suitable standard, E², erected on 35 the top plate, A. The lever E has at one end of it a hand piece or knob, 6, and is normally kept elevated by a spring, E³, placed in a spring-holder, E⁴, which also serves as an upward stop for the said lever or key, as in Fig. 1, the movement of the lever E by the said spring effecting 40 the movement of the said wheel B⁴ and carriage. The pawl D has a short arm provided with a knob, D⁵, by which the pawl may be removed from between the teeth of the wheel B⁴, and at such movement the short arm of the pawl D, acting on the short arm of the detent D⁴, pivoted at D⁵, removes it from engagement with the said toothed wheel, thus leaving the said wheel free and enabling the carriage at 45 such time to be removed by hand, as desired. This detent D⁴, having its fulcrum or pivot D⁵ on an ear of the lever E and connected by spring 8 with the pawl D, acts upon a pin, 9, in such time as to enable the hook of the detent to engage the wheel B⁴ only as the pawl reaches its upstroke, and consequently the movement of

the toothed wheel and carriage is prevented from overrunning said detent, thus enabling the apparatus to be run rapidly without improper spacing of the letters. The ink-ribbon a, of usual kind, is passed under suitable guides, a¹, between the spools a² a³, held frictionally on shouldered spindles a⁴ a⁵ in standards a⁶ a⁷. Each spindle is threaded at its outer end, and is screwed into the thread cut 75 in the standard a⁷, and in connection with a check-nut, a⁸, it will be obvious that the spindles may be rotated and moved longitudinally to place any desired part of the ink-ribbon between its edges under the type-wheel G. This 80 type-wheel is composed, chiefly, of a drum or suitable rim, an electrotype-strip, 12, having letters or characters thereon, (designated by the letter t in Fig. 1,) and a suitable axle, 13. The axle 13 is shown as countersunk at its 85 ends to receive pointed bearing-screws 14, one only of which is shown in Fig. 1; or it might be just the opposite, thus enabling the axle to be held and adjusted with the greatest nicety and with the minimum of friction. 90 The wheel G has attached to it at 15 one end of a spring, G², (see Fig. 3,) and the other end of the said spring is connected with a stud, 16, held in the lever E. (See detail, Fig. 4.) The spring operates to turn the type-wheel in one 95 direction to effect the winding of the cord 18 upon the drum, the said cord, after passing over the pulleys 19 20 on studs fixed to the frame, being connected with the index-slide d, mounted loosely on a guide-rod, d¹, held in 100 ears d². The index-slide d is provided with a finger or point, d³, which is adapted to enter the recesses or notches 22 in the index-plate 105 23, attached to the top plate, A, as herein shown, along its left-hand side, the said plate being provided opposite each hole with a letter or character corresponding with a letter or character upon the electrotype-strip of the type-wheel G, the letters and characters on the said wheel and the said index-plate being 110 so arranged with relation each to the other that the placing of the point d³ of the slide d in a recess or notch, 22, opposite the letter or character which it is desired to next print upon the paper will so actuate the wheel 115 through the cord and spring connected with it as to place the corresponding letter or character of the said type-wheel at the lower side thereof, to strike the ribbon a as the lever or key E is next depressed. The wheel G is provided 120 with a pin or projection, e, (see Fig. 1,) which strikes the stop 26 fast on the plate A whenever the pin d³ is in the outermost recess or notch of the series of recesses 22, that recess being called the "word-spacing" recess. 125 When the lever E is depressed with the pin e in line with the stop 26, the descent of the lever and wheel G is arrested before the latter strikes the ink-ribbon sufficiently to force it against the paper to print; but the lever is 130 not at such time arrested so as to prevent rotating the wheel B⁴. The top plate is pro-

vided with a downwardly-projecting pointer, *f*, so located with relation to the printing-point of the wheel *G* that, a wrong letter having been printed and erased, the right letter 5 may be printed in the exact spot by placing the spot where the erasure was made in line with, but at the opposite side of, the pointer, after which, by moving the platen longitudinally, the spot to receive the new impression 10 may be placed in exact position under the printing-point. The distance of the pointer from the printing-point is known by the operator as being equal to a certain number of lines represented by the scale *C*. The 15 carriage *B* is provided at its under side, near its rear end, with a downwardly-extended pawl, *g*, free to swing for a limited distance in the direction of the length of the carriage. This pawl, just before the carriage 20 reaches its farthest position in its movement toward the left, strikes behind the inclined free end of an alarm or click, *h*, made as a metal spring, (see Figs. 1 to 5,) and attached to the inner side of the back sill, *A*², and draws 25 the end of the said spring from the said sill, and as the end of the line is reached the pawl arrives opposite a notch, *h*², in the said spring, permitting it to snap off and strike the sill with a click, thus making an alarm. The 30 alarm or click *h* is made adjustable by screw *h*² in a slot therein to adapt it to paper of different widths. The spool *a*² is provided with a ratchet, 26, which is engaged and moved by the pawl 27 on the front part of the lever *E*. The lever *E* has its fulcrum on pointed screws 35 28 28.

In Fig. 1 the spring-like washers *y*, which act against the ends of the spools *a*² *a*³ to keep their opposite ends against the shoulders 40 of the spindles, *a*¹ *a*², are kept up against the spools 9 by pins or studs *y*², extended into holes in the said spindles.

I claim—

1. The stationary plate *A*, the key or lever 45 mounted thereon, the type-wheel carried by the said key or lever, and the ink-ribbon, combined with a platen and carriage made movable one on the other under the type-wheel, substantially as shown and described.

2. The stationary plate, the index 50 23 thereon, the index-slide and guide for the same, and cord 18, and pulleys or guides for it, combined with the type-wheel, the spring *G*, and the pivoted lever or key *E*, upon which the said type-wheel is adjustably mounted, substantially as described.

3. The stationary plate, the index 55 23 thereon, the index-slide, a guide for it, the type-wheel, its spring, the cord to connect the said type-wheel and index-slide, as described, and the lever *E* and pawl *D*, combined with the toothed wheel *B*¹, the rack moved by it, the laterally-movable carriage, and the longitudinally movable platen therein, substantially 60 as described.

4. The stationary plate, the index 65 23 there-

on, the index-slide, a guide for it, the type-wheel, its spring, the cord to connect the said type-wheel and index-slide, as described, and the lever *E* and pawl *D*, combined with the 70 toothed wheel *B*¹, the rack moved by it, the laterally-movable carriage and the longitudinally-movable platen therein, and with means, substantially as described, to automatically move the platen in the said carriage, as and 75 for the purposes set forth.

5. The ink-ribbon, the pivoted lever or key, the type-wheel adjustably mounted thereon, and the pawl and detent, combined with the wheel *B*¹, the rack-bar, and the carriage, substantially as described. 80

6. The ribbon *a*, type-wheel, lever to move it, and the carriage and stationary plate *A*, combined with the pointer *f*, to operate substantially as described. 85

7. The laterally-movable carriage, guides for it, platen with ink-ribbon, type-wheel, and lever to move it, combined with the top plate, *A*, cut away at its front side next the operator, as represented, to show the platen 90 and carriage, substantially as described.

8. The lever or key *E*, wheel *B*¹, rack, and carriage *B*, combined with the pawl *D* and detent *D*², each of the latter being provided with short arms, whereby the removal of the 95 pawl *D* from the wheel *B*¹ also removes the detent therefrom, substantially as described.

9. The carriage provided with the pointer, combined with the platen, provided with the scale marked to indicate lines, substantially 100 as described.

10. The top plate, the index-scale 23 thereon, provided with recesses or notches, the guide *d*², parallel with the said scale, and the index-slide mounted on the said guides so as to 105 be both slid and oscillated thereon, and provided with a point, *d*³, combined with a type-wheel, a cord to connect it with the said index-slide, a spring, *G*², and a lever or key to move the said type-wheel, all substantially as 110 described.

11. The lever or key, the type-wheel mounted thereon, and provided with the pin or projection *e*, combined with the top plate and the stop 26, to operate to arrest the downward movement of the type-wheel, to obviate printing, substantially as described. 115

12. The ink-ribbon, the spools, the screw-threaded and shouldered spindles to hold the spools, the standard *a*¹, threaded to receive the 120 threaded part of the spindle, and the check-nuts to provide for lateral adjustment of the spindles and their spools, substantially as described.

13. The ink-ribbon spool, its attached 125 ratchet and spindle to hold the said spool and ratchet, combined with the type-wheel moving lever or key, and with a connected pawl to engage the said ratchet and turn the said spool, substantially as described. 130

14. In a type-writer, a bed-plate provided with an index, 23, at right angles to the line

being printed, and a type-wheel and lever or key upon which the said wheel is mounted and by which it is moved vertically, combined with a cord to move the wheel, and an index-
5 slide, and a guide for it to insure the movement of the said slide in a line out and in from the operator, substantially as described.

In testimony whereof we have signed our

names to this specification in the presence of two subscribing witnesses.
